UNITED STATES PATENT OFFICE.

CHARLES BAIA, OF PALISADE, AND ALFRED ADERENTE, OF JERSEY CITY, NEW JERSEY, ASSIGNORS TO SLIP-ON CIGAR LIGHTER COMPANY, INCORPORATED, OF NEW YORK, N. Y., A CORPORATION OF NEW JERSEY.

CIGAR AND CIGARETTE LIGHTER.

Application filed April 10, 1924. Serial No. 705,475.

To all whom it may concern:

Be it known that we, CHARLES BAIA, a citizen of the United States, and a resident of Palisade, in the county of Bergen and

5 State of New Jersey, and ALFRED ADERENTE, a citizen of the United States, and a resident of Jersey City, in the county of Hudson and State of New Jersey, have invented a new and Improved Cigar and Cigarette Lighter, 10 of which the following is a full, clear, and exact description.

This invention relates particularly to a device for lighting cigarettes, cigars and the like, in which an electric resistance is employed to generate an ignition temperature.

One object of the invention is to provide a construction wherein the heating element is normally disconnected from the source of electrical supply, but is moved into electrical connection therewith by the act of pressing the cigarette or cigar against said heating element.

Another object is to encase the heating device in such a way that it is not likely to be moved accidentally into position to close the electric circuit therethrough.

A still further object is to provide an ash tray in a convenient location with respect to the heating element to collect the ashes 30 from the cigar or cigarette.

Other objects of the invention will appear in the following complete specification of our invention, when taken in connection with the accompanying drawings in which:

35 Fig. 1 shows the complete cigar and cigarette lighter mounted on a fragment of a radio panel board,

Fig. 2 shows a portion of the lighter with the ash tray and protecting casing removed,

40 Fig. 3 is a section taken on the line 3—3 of Fig. 2, but with the casing in place, and

Fig. 4 is a section taken on the line 4—4 of Fig. 1.

Referring now to the drawing, 10 indicates a base plate of non-conducting material. This base plate carries two contact posts 11 formed with threaded shanks 12, which pass through the base plate 10, and are provided with nuts 13 and 13', which

50 bear on opposite sides of the plate 10 and clamp the contact posts securely thereto. It will be observed that the plate 10 is countersunk on the rear side thereof to re-

ceive the rear locking nuts 13', so that they will lie flush with the rear face of the base 55 plate 10.

The base plate 10 is perforated near the center thereof to receive a post 14, which at its outer end carries a plate 15 of non-conducting material. A light compression 60 spring 16 surrounds the post 14, bearing at its outer end against the plate 15, and at its inner end against a washer 17, the latter, in turn, bearing against the base plate 10. A nut 18 threaded on the post 14 serves as 65 a stop to limit the action of spring 16.

Mounted on the plate 15 is the heating element which consists of a coil of resistance wire or ribbon 19 wound around a plate of mica or other non-conducting material 20. 70 The ends of the resistance wire or ribbon are secured to binding screws 21 which project through the plate 15, being clamped thereto by nuts 22. By pressing against the plate 15, contact is made between the binding screws 21 and the contact posts 11, closing the electric current through coil 19, and on releasing the pressure, the spring 16 returns the plate 15 to normal position, 75 breaking the contact.

Dispersion of heat from the coil 19 is limited by a strip of mica or other heat insulating material 23, between the coil of the plate 15. In order to guide the heating element when it is being moved into or out 85 of contact position, we provide two walls 24 above and below the heating element. These walls are L-shaped in cross section, the foot 25 of each wall being riveted or otherwise secured to the base plate 10, as indicated 90 at 26 (Fig. 2).

Inadvertent depressing of the heating element and accidental burns are prevented by a casing 27 provided with an opening 28, through which a cigar or cigarette may be 95 inserted and brought into contact with the resistance coil 19. It will be observed that the guide walls 24 cooperate with the side walls of the casing 27 to form a rectangular pocket in which the plate 15 is operated and 100 serve to guard against rotary displacement of said plate.

As indicated by broken lines in Fig. 1, our lighter may be applied to the panel board 29 of a radio receiving set. The device is 105 secured to the panel by contact posts 12

which pass through the panel board 29 (see Fig. 4) and are secured thereto by means of nuts 30. The posts 12 are also provided with nuts 31 for clamping the conducting ends of the wires 32 thereto. The wires 32 may be connected to the "A-battery" of the radio receiving set to furnish the current used to heat the resistance coil 19. The casting 27 is secured to the lighter by means of 10 screws 33 which pass therethrough and also through the panel board 29, being clamped to the latter by means of nuts 34.

Depending from one of the screws 33 is an ash tray 34 which may be of any suitable form. The tray may be swivelled about the screw 33 to an inverted position so as to dump out the contents thereof. It will be observed that this ash tray is conveniently located with respect to the lighter so that 20 a partially consumed cigar or cigarette may be brushed clean of its ashes before being inserted through the hole 28 against the resistance coil 19, and so as to catch incandescent particles that might drop from the 25 cigar or cigarette when the lighter is used.

The spring 16 is so light that it may be compressed by the mere act of pressing a cigarette against the resistance coil and as soon as contact is made between the binding 30 screws 21 and the contact posts 11, there will be a flow of current through the resistance coil which will heat it up to incandescence or up to a temperature sufficient to ignite the cigarette or cigar.

35 The gap separating the binding screws 21 and the contact posts 11 may be adjusted by means of the nut 18, which bears against the panel board 29. It will be evident that by adjusting the contact posts 11 and correspondingly adjusting nut 18, the strength 40 of spring 16 may be regulated.

When the lighter is used on a radio panel board current can be taken from the "A-battery" without in the least disturbing the 45 operation of the receiving set during the lighting of a cigarette or cigar. Of course, if desirable, an entirely separate source of current could be used in connection with this lighter.

50 While we have shown this device as ap-

plied to the panel board of a radio receiving set, it will be evident that it could be applied to other panel boards, and is capable of many other applications without departing from the spirit and scope of our invention. For instance, the device might be used on the dash board of an automobile or it might be mounted on a special panel for use in a cigar store or in the home, being supplied with electric current from any suitable source. Hence, we desire to have it clearly understood that we do not limit ourselves to the particular form of mounting shown in the accompanying drawings.

We claim:

1. In a cigar or cigarette lighter, a base, contact posts thereon adapted to form terminals of an electric circuit, a sliding support, a resistance unit mounted on said support in position to be moved into electrical contact with said posts, a spring adapted to hold the resistance unit out of contact with the posts, and means for adjusting the strength of said spring.

2. In a cigar or cigarette lighter a base, terminals for an electric circuit mounted on said base, an electrical resistance unit, a resilient support for said unit adapted normally to hold the unit out of contact with said terminals, but permitting the unit to be 80 pressed into electrical contact with the terminals, and means for adjusting the gap normally separating said unit from said terminals.

3. In a cigar or cigarette lighter, a resistance unit, two contact members adapted to complete an electric circuit through the resistance unit, and a resilient support forming no part of the electric circuit adapted to hold the resistance unit normally out of 90 contact with said contact members.

4. In a cigar or cigarette lighter, a base, a single spring spindle, a resistance unit mounted on said spindle, and two contact members adapted on depression of the resistance unit to complete an electric circuit through said resistance unit, said spindle forming no part of the electric circuit.

CHARLES BAIA.
ALFRED ADERENTE.
